HOWARD E. HUGHES, OF HOUSTON, TEXAS, ASSIGNEE TO SHARP-HUGHES TOOL COMPANY, OF HOUSTON, TEXAS, A CORPORATION OF TEXAS.

ROTARY DRILL.

1,143,273.

Specification of Letters Patent. Patented June 15, 1915.

Application filed February 24, 1914. Serial No. 820,879.

To all whom it may concern:

Be it known that I, HOWARD E. HUGHES, a citizen of the United States, residing at Houston, Texas, have invented a certain new and useful Improvement in Rotary Drills, of which the following is a full, clear, and exact description, such as will enable others skilled in the art to which it appertains to make and use the same.

10 This invention relates to rotary drills such as are used in well-drilling operations.

As is well understood by those skilled in the well-drilling art, it is the universal practice in drilling a well with a rotary 15 drill to pump water down through the hollow stem of the drill so as to flush out the material that is disintegrated by the cutters on the bit or drill that is connected to the lower end of the stem, the head or shank of 20 the drill being provided with water-courses or passageways from which the flushing water escapes. A number of water-courses are formed in the head or shank of the drill, and usually in such a manner that the 25 jets or streams of water which emerge therefrom come together or act on each other so that the force of one jet or stream is partially neutralized by the other. The result is that the disintegrated material tends to 30 pack in the hole and adhere to the cutting devices on the head or shank of the drill, thus greatly reducing the efficiency of the drill. Furthermore, as one stream or jet of flushing water tends to counteract the 35 force of the other, more or less back pressure is created on the pump, thus requiring more power to operate the pump than would be necessary if the jets or streams did not come together or act on each other 40 before the force of same had been spent.

The main object of my present invention therefore is to provide a drill or drill bit which is so designed that the full force of each jet or stream of wash-water is utilized 45 to stir up the disintegrated material and dislodge it from the cutting devices on the drill.

Another object is to provide a drill or drill bit which is so designed that a jet or stream of wash-water will be discharged therefrom in such a manner that the water tends to swirl upwardly around the head or shank of the drill in a circular path opposite to the direction of rotation of the 55 head. And still another object is to pro-

vide a drill or drill bit which comprises means for discharging jets of water downwardly from the lower end of the head, at an angle to a horizontal plane, into the advancing paths of the cutting devices on the head. To this end I have devised a rotary drill in which the water-courses or passageways are so formed that the jets or streams of wash-water which emerge therefrom will not neutralize or counteract the force of each other, and, furthermore, will be discharged in such a manner that the water tends to swirl upwardly in a circular path opposite to the direction of rotation of the drill head in escaping from the bottom of the hole.

My invention is applicable to drills or drill bits that are provided either with stationary cutters or with rotatable cutters, and while I have herein illustrated my invention embodied in two different types of rotatable cutter boring drills now in general use, I wish it to be understood that my invention is applicable to various other types of rotary drills.

Figure 1 of the drawings is a side elevational view of a drill constructed in accordance with my invention and provided with substantially disk-shaped rotatable cutters; Fig. 2 is a bottom plan view of said drill; Fig. 3 is a vertical sectional view of said drill taken on approximately the line 3—3 of Fig. 1; Fig. 4 is a side elevational view of a drill constructed in accordance with my invention and provided with substantially frusto-conical-shaped rotatable cutters; and Fig. 5 is a top plan view on a reduced scale of the drill shown in Fig. 4.

Referring to Figs. 1 to 3 of the drawings, A designates the head of the drill provided at its upper end with a screw-threaded portion 1 that is adapted to be surrounded by the usual coupling sleeve which connects the head to the hollow drill stem, not shown, through which water is pumped to flush the disintegrated material from the bottom of the hole. A pair of substantially disk-shaped cutters B are rotatably mounted on the drill head A in an inclined position, as shown in Fig. 1, and water-courses 2 are formed in said head to form passageways for the flushing water that is pumped down through the drill stem. The drill shown in Figs. 1 to 3 is provided with two water-courses or passageways 2 whose lower ends 3

terminate in the bottom end face 4 of the head, as shown in Fig. 2. Instead of having the water-courses or passageways 2 extend through the head in a substantially straight line from the upper end of the head to the lower end face thereof, as has heretofore been the usual practice, I form said water-courses or passageways in such a manner that the jets or streams which emerge therefrom will be discharged downwardly and outwardly in opposite directions from the head, thereby preventing one jet from counteracting the force of the other, and also causing the water to swirl upwardly around the head in a circular path. In the drill shown in Figs. 1 to 3 each of the water-courses comprises a substantially vertically-disposed portion that leads downwardly from the upper end of the head to a point adjacent the bottom of the head and a substantially horizontally-disposed portion 2* that is inclined downwardly with reference to a horizontal plane, and which branches laterally from said vertically-disposed portion to the lower discharge end 3 of the water-course, as illustrated in Fig. 3 of the drawings. When the drill is in operation, the jets of water which escape from the lower ends of the water-courses will be discharged downwardly toward the bottom of the hole and also outwardly or laterally in opposite directions from the drill head toward the side wall of the hole into the advancing paths of the cutters, as indicated by the arrows in Fig. 2, the rotary motion of the head of the drill and the angle at which the jets discharge from the head causing the water to swirl upwardly in a circular path opposite to the direction of rotation of the drill head. By forming the water-courses in such a manner that the jets of water are discharged from the bottom end face 4 of the head in opposite directions and at points between the cutters B, the full force of each jet is exerted on the disintegrated material, and consequently said material will not pack in the hole or cling to the cutters.

The drill illustrated in Figs. 4 and 5 is provided with approximately frusto-conical-shaped cutters B' that are rotatably mounted on the head A' of the drill in such a manner that their axes of rotation incline downwardly and inwardly toward the longitudinal center of the drill head, and the water-courses or passageways 20 that are formed in the head lead downwardly from the upper end of the head to discharge openings 30 formed in the lower end face of the head at points above the cutters B' and between said cutters. The water-courses 20 are inclined in such a manner that the jets of water which escape from the lower ends of same will be discharged downwardly into the advancing paths of the cutters and outwardly in op-

posite directions toward the side of the hole; as indicated by the arrows in Fig. 5, the jets being discharged from the head tangentially in circular paths opposite to the direction of rotation of the drill head. While the water-courses 20 of the drill shown in Figs. 4 and 5 are formed in a slightly different manner from the water-courses of the drill shown in Figs. 1 to 3, nevertheless, the same results are accomplished, namely, the full force of each jet is utilized to stir up the disintegrated material and prevent it from packing, no back pressure is created on the pump, and the water swirls upwardly in a circular path in escaping from the bottom of the hole.

While I have herein illustrated two different types of rotary drills, each of which is provided with two water-courses or passageways for the flushing water, I wish it to be understood that my invention is applicable to various other types of rotary drills, and that the particular number of water-courses or passageways in the head of the drill are immaterial so far as my broad idea is concerned.

Having thus described my invention, what I claim as new and desire to secure by Letters Patent is:

1. A rotary boring drill having a head or shank provided with a water-course or passageway which is so disposed that the stream of water which emerges therefrom will be projected outwardly from the head and also downwardly at such a slight angle that when it strikes the bottom of the hole it tends to swirl upwardly around the head in a circular path opposite to the direction in which the head of the drill is rotating.

2. A rotary boring drill having a head or shank provided with a water-course or passageway which is so formed that a jet of water will be discharged from the lower end face of the head toward the side wall of the hole and downwardly against the material on the bottom of the hole at such a slight inclination to a horizontal plane that it will be deflected upwardly around the drill head in a circular path opposite to the direction of rotation of the head.

3. A rotary boring drill provided with a cutting device, and having a passage for discharging a jet of water toward the advancing edge of said cutting device and downwardly against the material on the bottom of the hole, the lower portion of said passage being inclined at such a slight angle to a horizontal plane that the water and disintegrated material will be discharged upwardly around the head of the drill in a circular path opposite to the direction of rotation of the head.

4. A rotary boring drill provided with a rotatable cutting device and having means for projecting a jet of water downwardly

- onto the material lying in advance of the path of the cutting device and at such an angle that the disintegrated material is flushed laterally toward the side of the hole.
5. A rotary boring drill comprising a head provided with a cutting device, and a water-course or passageway formed in said head in such a manner that a stream or jet of water will be projected downwardly and outwardly from said head in a circular path opposite to the direction of rotation of the drill head and toward the advancing edge of the cutter.
6. A rotary boring drill equipped with a rotatable cutter and provided with means for projecting a stream of water downwardly toward the bottom of the hole and outwardly toward the side of the hole in a circular path opposite to the direction of rotation of the drill.
7. A rotary boring drill comprising a head, and a rotatable cutter on said head, said head having a water course or passageway the lower end of which is inclined at a slight angle to a horizontal plane so that a jet of water will be discharged toward the advancing edge of the cutter and downwardly against the disintegrated material at the bottom of the hole at such an angle that said water and material will be carried upwardly around the drill head in a circular path opposite to the direction in which the head of the drill is rotating.
8. A rotary boring drill comprising a head or shank provided with a cutting device, and means for causing a jet of water to be discharged downwardly and tangentially from the lower end of the head.
9. A rotary boring drill comprising a head or shank provided with a cutting device, and means for causing a jet of water to be discharged downwardly and tangentially from the lower end of the head and in a circular path opposite to the direction of rotation of the head.
10. A rotary boring drill comprising a head provided with a cutting means, and means for causing a plurality of jets of water to be discharged downwardly from the head and outwardly from the head toward the side wall of the hole in paths that do not meet or intersect, thereby preventing the force of one jet from being neutralized by a different jet.
11. A rotary boring drill comprising a head provided with a cutting means, and a plurality of water-courses formed in said head in such a manner that streams of water are discharged downwardly and outwardly from the head in a circular path opposite to the direction of rotation of the drill head and in such a manner that the full force of each jet is utilized to stir up the disintegrated material and prevent it from adhering to the cutting means on the head.
12. A rotary boring drill provided with a plurality of cutting devices and with passages for causing jets of water to be discharged toward the advancing edges of said cutting devices and also downwardly against the material on the bottom of the hole, the lower portion of said passages being inclined at such a slight angle to a horizontal plane that said water and disintegrated material will be deflected upwardly around the drill head.
13. A rotary boring drill provided with a plurality of rotatable cutters and with means for causing a plurality of streams of water to be discharged downwardly toward the bottom of the hole and outwardly toward the side of the hole in circular paths opposite to the direction of rotation of the drill head.
14. A rotary boring drill comprising a head or shank provided with water-courses or passageways which are so formed that a plurality of jets of water will be discharged downwardly and tangentially from the lower end face of the head in such a manner that the force of one jet is not neutralized by the force of a different jet.
15. A rotary boring drill comprising a head provided with rotatable cutters and angularly-disposed water-courses in the head that terminate in the lower end face of the head in such a manner that the streams of water which emerge therefrom are projected downwardly from the head toward the bottom of the hole and also laterally toward the side of the hole.

In testimony whereof I hereunto affix my signature in the presence of two witnesses, this 16th day of February 1914.

HOWARD R. HUGHES.
